(57) **CLAIM**

The ornamental design for a bowl with handle as shown and described.

DESCRIPTION

FIG. 1 is a top, front, right perspective view of a bowl with handle showing my new design.

FIG. 2 is a bottom, rear, left perspective view thereof.

FIG. 3 is front view thereof.

FIG. 4 is a rear view thereof.

FIG. 5 is a top view thereof.

FIG. 6 is a bottom view thereof.

FIG. 7 is a left view thereof.

FIG. 8 is a right view thereof.

FIG. 9 is a top, front, right perspective view of the bowl with handle shown in use with environmental subject matter of an exemplary lid.

FIG. 10 is a bottom, rear, left perspective view thereof.

FIG. 11 is front view thereof.

FIG. 12 is a rear view thereof.

FIG. 13 is a top view thereof.

FIG. 14 is a bottom view thereof.

FIG. 15 is a left view thereof; and,

FIG. 16 is a right view thereof.

The broken lines are shown for the purpose of illustrating both parts of the article as well as environmental subject matter. None of the broken lines form part of the claimed design.

1 Claim, 16 Drawing Sheets
